UNITED STATES PATENT OFFICE.

JOHN ALWYN KELLER, OF BAY SHORE, NEW YORK, ASSIGNOR TO KELLER PRINTING COMPANY, OF NEW YORK, N. Y., A CORPORATION OF NEW YORK.

MACHINE FOR PRINTING TICKETS.

Application filed March 16, 1923. Serial No. 625,574.

To all whom it may concern:

Be it known that I, JOHN ALWYN KELLER, a citizen of the United States, and resident of Bay Shore, in the county of Suffolk and 5 State of New York, have invented certain new and useful Improvements in Machines for Printing Tickets, of which the following is a specification.

This invention relates to machines for 10 printing tickets, and it has particular relation to an improved mechanism for imprinting the "lot numbers" or other identifying data successively upon clothing tickets which are to be attached to garments or upon other 15 or analogous tickets which are fed through the machine in continuous strips comprising successively the respective ticket units.

The object of my invention is to provide 20 a simple and improved mechanism of the character set forth, which will possess advantages in point of convenience and delicacy of adjustment, positive and effective action, economy in construction and general efficiency.

25 In the drawings—

Figure 1 is a side view of the mechanism embodying my invention.

Fig. 2 is a face view of the mechanism shown in Fig. 1.

30 Fig. 3 is a side view opposite to that shown in Fig. 1.

Fig. 4 is a vertical sectional view on the line 4—4, Fig. 1.

Fig. 5 is a detail cross-section on the line 35 5—5, Fig. 4.

Fig. 6 is a detail cross-section on the line 6—6, Fig. 4.

Fig. 7 is a detail side view of the adjustable bushing which constitutes the bearing 40 for the main revoluble type-disc shaft.

Fig. 8 is an end view of said bushing.

Fig. 9 is a perspective view of one of the type-discs.

45 Corresponding parts in all the figures are denoted by the same reference characters.

Referring to the drawings, 14 designates a suitable upright frame which supports in relative position the operative parts herein-after described. A main revoluble shaft, 15, 50 is provided to carry the printing media and is mounted in projective position from the framework. Said shaft carries a fixed collar, 16, which may be adjustably connected with the shaft by a set screw, as at 17, 55 and constitutes the hub of a driving gear,

18. Under some preferred conditions, said collar-hub of the driving gear may be permanently fixed to the shaft without adjustable connection. Beyond the gear-collar 16, the shaft is provided with a fixed or integral 60 rib, 19, extending longitudinally a suitable distance and projective laterally from the cylindrical circumference of the shaft, which rib forms a key for locking the type-discs against rotary movement on the shaft. 65

The type-discs, 20, which constitute the printing media, are respectively formed by a metallic plate having a central or axial cylindrical opening, 21, corresponding to the shaft 15, and a radial recess, 22, extending 70 from said opening and corresponding to the fixed key 19 of the shaft. Said discs have a circular periphery, and at equidistant points thereon are provided with projective type-heads, 24, having the characters to be printed. In the present conditions as illustrated, for printing "lot numbers," these characters are numbers, each of the plural type-heads 75 of the respective disc carrying a corresponding number, so that when a plurality of the 80 type-discs are assembled together successively and side by side upon the shaft 15 they will collectively form a printing drum having at each cross-series of type-heads the desired series of numbers representing the 85 "lot number" for which the mechanism is set. The type-discs preferably carry a plurality of printing-heads for the usual multiple-speed action, so that with one revolution of the main shaft 15 the desired numbers or identifying data are imprinted upon a successive plurality of ticket units as the 90 continuous ticket-strip passes through the machine.

Such printing discs have been heretofore 95 employed, and in my invention the set of discs is mounted directly upon the main revoluble shaft 15 and locked thereon by the engagement of their recess 21 with the fixed rib-key 19 carried by the shaft, the 100 series of discs thus mounted side by side being maintained in such relative position and locked connection with the shaft by abutment at one end against the outer end of the fixed gear-hub 16 and at the other 105 end by a thumb-nut, 25, screwed upon the threaded outer terminal end, 26, of the shaft 15, and having its inner face abutting and bearing against the outer end of the assembled series of discs. The member 25 for thus 110

retaining the removable type-discs in direct connection with the shaft 15 is preferably a wing-nut, for convenient operation, and constitutes a clamp acting directly 5 against the set of type-discs, and its inner clamping face is preferably recessed or chambered, as at 27, to afford accommodating space for the fixed key-rib 19 of the shaft in circumstances where the number of 10 type-discs employed would leave an outer end portion of the rib projecting beyond the set of discs.

In the operative conditions and service of ticket-printing mechanisms of the class to 15 which my invention relates, it is important to assure a positively-maintained mounting of the type-discs in connection with the main shaft, to avoid "slippage" or any relative variation of the position of the mounted and assembled discs, which would cause 20 inaccuracy of printing or "blurring" of the imprint, and my improvements are designed to effectively meet these conditions by providing a positive locked connection of 25 the type-discs directly to and upon the main shaft, whereby the movement of the shaft and discs must be absolutely coincident, and a clamping member, 25, which is likewise directly carried by the shaft and itself directly 30 bears against the set of type-discs. This effective construction also presents the advantages of simplicity and economy in manufacture and convenience in operation and use.

35 It is also an important desideratum that a very delicate adjustment of the plane of the type-discs be permitted, to compensate for very slight variation in the thickness of the paper ticket-strips which are fed 40 through the mechanism between the printing-heads 24 and an underlying platen or bed. In such adjustment the plane of the type-discs is varied by adjustment of the plane of the carrying main-shaft, and the 45 means for this adjustment as comprised in my invention is designed to enable extreme delicacy and convenience in the adjustment action.

For this purpose, my improvements comprise 50 a bushing member, 28, having a cylindrical circumference, as at 29, turnably mounted in a corresponding cylindrical opening in the frame 14. Said bushing has a longitudinal cylindrical bore, 30, through 55 which the revoluble main type-disc shaft 15 passes and which constitutes the bearing therefor. The bore bearing 30 for the shaft is on a plane eccentric to the center or axis of the bushing in its turnable adjustable 60 movement upon its cylindrical seat 29 in the frame 14. Thus, a slight turning movement of the eccentric-bearing bushing will effect a very delicate variation in the plane of the type-disc shaft 15.

65 To lock the turnable bearing bushing in

its cylindrical seat, and enable convenient manipulation for adjustment and fixed maintenance thereof, the bushing is provided, at its end beyond its cylindrical circumference 29, with a circumferential 70 flange, 31, adapted to bear against the face of the frame 14 adjacent the gear-hub 16, and its opposite end is externally threaded, as at 32, and carries a lock-nut, 33, adapted to seat against the opposite face of the 75 frame 14, whereby the turnable bushing is securely clamped in its cylindrical seat in the frame between the flange 31 and nut 33. At the end of the type-disc shaft beyond the eccentric-bearing bushing, a collar, 34, is 80 carried by the shaft and co-acts with the fixed gear-hub 16 to retain the shaft in its revoluble operative status, said collar being positioned by means of a set-screw 35.

In my improved mechanism is also comprised the inking drum or roller which contacts with the type-heads 24 of the printing discs and supplies the ink thereto. This drum, 36, is suitably mounted above the type-discs and has the usual felt ink-pad, 37, at its cylindrical surface.

The delicacy of adjustment movements afforded by my improvements renders it unnecessary that the inking drum be gear-driven in a revoluble movement, and in my 95 invention the drum is mounted as an "idler" which will be advanced in a revoluble step-movement by its contact with the type-heads of the printing-discs in the revolution of the discs. Said idler inking-drum 36 is 100 turnably mounted upon a fixed stub-shaft, 38, between retaining means at the outer end of the shaft (such as a cross-pin, 39) and a circumferential shoulder, 40, upon the shaft at the opposite side of the drum. Said fixed 105 stub-shaft 38 is preferably adjustably mounted, to govern pressure of the inking drum upon the type-heads 24, and for this purpose the top end of the frame-arm 14 is provided with an open-end slot, 41, in which is conveniently placed and seated the inner end of the stub-shaft, and the latter is secured in adjusted fixed position and connection with the frame 14 by the abutment of a shoulder, 42, upon the shaft, against one 115 face of the frame and the clamping action of a set-nut, 43, carried upon the threaded end, 44, of the shaft, against the opposite face of the frame.

45 designates a gear suitably comprised in 120 the driving mechanism of the machine, which meshes with the gear 18 of the type-disc driving-shaft 15 to impart motion to the latter.

A platen or bed of any suitable construction, as indicated at 46, is mounted in relative position beneath the printing drum formed by the assembled type-discs, and the continuous ticket-strip, shown at 47, is fed in and through the mechanism between the 125 130

type-heads 24 and said platen or bed. The latter has a curved periphery, and is preferably of circular or drum form and revolvably mounted, as is usual in this class of 5 ticket-printing machines, and the respective cross-series of type-heads 24 of the revolving type-discs contact with and imprint upon the respective spaced units of the continuous ticket-strip 47 at the apex of the successive 10 arcs of the curved periphery of the platen in the revolution thereof.

The delicate adjustment of the type-disc shaft 15, to compensate for slight variation in the thickness of the paper ticket-strips 47 15 or for wear of the type-heads 24, is therefore effected towards and from the periphery of the platen or bed 46.

The operation and advantages of my improvements will be readily understood by 20 those skilled in the art to which my invention appertains. The mechanism is characterized by extreme simplicity in construction and therefore economy in manufacture, affords direct connection of the printing 25 media with its actuating shaft and therefore secures a positive and effective operation, and enables very delicate adjustment for conditions of perfect efficiency and with maximum certainty and convenience.

30 I do not desire to be understood as limiting myself to the detail features of construction and arrangement as herein shown and described, as it is manifest that variations and modifications therein may be resorted to, in the adaptation of my invention to varying conditions of use, without departing from the spirit and scope of the invention and improvements. I therefore reserve the right to all such variations and modifications 35 as properly fall within the scope of my invention and the terms of the following claims.

Having thus described my invention, I claim and desire to secure by Letters Patent: 45

1. In a machine of the class described, for printing successively upon the ticket units of a continuous ticket-strip, a revolvble shaft, type-discs having printing characters at their periphery and keyed in 50 locked connection directly to and upon said shaft, whereby said type-discs have a fixed mounting directly on the shaft itself, an impression platen or bed positioned parallel to said revolvble shaft, a framework having 55 a supporting seat, a bushing-block turnably mounted in said seat and having a cylindrical bore in a longitudinal plane eccentric to the axis of said bushing in its turnable movement, said printing-disc shaft 60 having its revolvble bearing in said bore of the bushing-block, and means for locking 65 said bushing-block in fixed position in its seat, whereby delicate adjustment of the plane of the printing-disc shaft to compen-

sate for very slight variation in the thickness of the paper ticket-strips passing between the type-discs and the platen may be effected by slight movement of the turnable bushing-block in its seat. 65

2. In a machine of the class described, 70 for printing successively upon the ticket units of a continuous ticket-strip, a revolvble shaft having a fixed rib extending in a longitudinal plane and projective at the periphery of the shaft, type-discs having 75 printing characters projective at their periphery and provided with a central opening corresponding to said shaft and its rib and constituting means whereby said type-discs are mounted directly on said shaft and in fixed position and locked connection 80 directly thereto, means for clamping said discs in their assembled locked connection directly to and upon said shaft, an impression platen or bed positioned parallel to 85 said revolvble shaft, a frame-work having a cylindrical seat, a bushing-block having a cylindrical circumference corresponding to and turnably mounted in said seat and having a cylindrical bore in a longitudinal plane eccentric to the axis of said bushing in its turnable movement, said printing-disc shaft having its revolvble bearing in said bore of the bushing-block, and means for locking 90 said bushing-block in fixed position in its cylindrical seat, whereby delicate adjustment of the plane of the printing-disc shaft to compensate for very slight variation in the thickness of the paper ticket-strips 95 passing between the type-discs and the platen may be effected by slight movement of the turnable bushing-block in its seat. 100

3. In a machine of the class described, 105 for printing successively upon the ticket units of a continuous ticket-strip, a revolvble shaft, printing media mounted circumferentially upon said shaft and having peripheral printing characters, an impression platen or bed positioned parallel to 110 said revolvble shaft, a frame-work having a supporting seat, a bushing-block carried by said seat and turnably movable therein and having a cylindrical bore in a longitudinal plane eccentric to the axis or center of said bushing in its turnable movement, said printing-media shaft having its revolvble bearing in said bore of the bushing-block, whereby delicate adjustment of the plane of the printing-media shaft to compensate for very slight variation in the thickness of the paper ticket-strips passing 115 between the printing media and the platen may be effected by slight movement of the turnable bushing-block in its seat. 120

In testimony whereof I have signed the foregoing specifications.

JOHN ALWYN KELLER.
